(57) **CLAIM**

The ornamental design for a support element for scalpel having a transparent universal blade fitting, as shown and described.

DESCRIPTION

FIG. 1 is a front perspective view of a support element for scalpel having a transparent universal blade fitting;

FIG. 2 is a rear view of the support element for scalpel having a transparent universal blade fitting;

FIG. 3 is a front view of the support element for scalpel having a transparent universal blade fitting;

FIG. 4 is a left side view of the support element for scalpel having a transparent universal blade fitting;

FIG. 5 is a right side view of the support element for scalpel having a transparent universal blade fitting;

FIG. 6 is a top view of the support element for scalpel having a transparent universal blade fitting; and,

FIG. 7 is a bottom view of the support element for scalpel having a transparent universal blade fitting.

The broken lines in FIGS. 1-3 illustrate portions of the support element for scalpel having a transparent blade fitting that form no part of the claimed design.

1 Claim, 3 Drawing Sheets
